ELECTRIC FUSE ASSEMBLY

Max M. Lear, Jr., Lakewood, N. Y., assignor, by mesne assignments, to Monarch Electric Corporation, Jamesstown, N. Y., a corporation of Delaware

Application October 6, 1953, Serial No. 384,500

4 Claims. (Cl. 200—131)

This invention relates to electric fuse assemblies, and is more particularly concerned with clamping structures included in such assemblies for holding renewable fuse links.

A feature of the invention is the provision of a clamping device which may be employed with fuse links having notches at their ends or with fuse links having unnotched ends.

Another feature is the provision of a clamping device having locating parts to assure proper positioning of the clamp and of fuse links.

A further feature is the provision of a clamping device associated with heat-dissipating elements and effective in conjunction with a fuse link for determining the operating condition at which the fuse link will act.

With these and other features and objects in view, as will appear in the course of the following description and claims, an illustrative form of the invention is shown on the accompanying drawings, in which:

Fig. 1 is an axial section through a cartridge type of fuse structure including the clamping and heat-dissipating elements, and with an unnotched fuse link in position.

Fig. 2 is a top plan view of the removable internal structure of Fig. 1.

Fig. 3 is a perspective view of a clamping element.

Fig. 4 is a view showing a part of the clamping structures with an end-notched fuse link in position.

Fig. 5 is a perspective view of an unnotched fuse link as used in Figs. 1 and 2.

Fig. 6 is a perspective view of an end-notched fuse link as shown in Fig. 4.

In the drawings, an outer sleeve 10, for example of an insulating and fire-resistant material such as vulcanized fiber, has secured therein the end ferrules 11, 12 of metal such as brass, each having an external thread for receiving the respective annular end cap 13, 14. Inner and outer baffles or closures 15, 16 are provided within the cap 13 and held thereby against the end of the ferrule 11: these baffles have apertures 17, 18 through which extends one terminal blade 20 of a removable internal structure. The end cap 14 similarly contains a baffle or closure plate 21. It is preferred to form the end caps with a thinned outer end, so that the baffles rest against an internal shoulder, and then to spin or curl this thinned end inward to engage the outer face of the baffle, wherewith the end cap 14 can be rotated relative to the baffle 21.

The removable internal assembly has the terminal blades 20, 25 which are received by the clips of the usual fuse block and serve for the passage of the electric current. Each blade has a narrower portion 26 located within the sleeve 10 when the parts are assembled, whereby shoulders 27 are provided against which bear the baffle plates 28, 29. At one end the baffle plate 28 conforms to the baffle 15 and upon assembly is located in the plane of the baffle 15: at this end a second inner baffle 30 is provided of circular shape and size to fit within the end ferrule 11 with an annular space through which the heated gases may pass and move along a tortuous path

2

provided by the baffles and therewith be cooled before gaining the outer atmosphere.

At the other end, the baffle 29 rests against the end of the ferrule 12 after assembly; and a second inner baffle 31, of a size slightly smaller than the inside of the ferrule 12, has projecting lugs 32 which fit in notches 33 of the ferrule 12.

The baffles 28, 30 and 29, 31 have apertures closely receiving the respective blade portions 26 and are held firmly against the shoulders 27 by staked metal 34 displaced from these portions.

The end terminal and baffle assemblies are held rigidly together and at distances such that the inner baffles 28, 29 are in proper position in the ferrules and against the outer baffles, by a bridge 40 of insulating material such as vulcanized fiber, with screws 41 which are threaded into the respective blade portions 26. Between the portions 26 and the bridge 40, at each end, are provided the heat-dissipating fins 42 which have apertures for the screws 41: these fins may be of flat heat conductive metal stock and are positioned parallel to one another and to the portions 26 and bridge 40, spacing washers 43 being employed to fix the relative positions.

The fins 42 also have apertures for receiving the heads 25 of clamping bolts 50 which extend through apertures of the blade portions 26, and through apertures in the clamp blocks 51, so that the associated nuts 52 and washers 53 are effective to draw the blocks 51 toward the respective blade portions 26. As shown in Fig. 3, each clamp block 30 51 has a foot 55 with projecting lugs 56 for entering the alining recesses 57 in the blade portion 26 so that the blocks 51 are fixed in position against rotation about the axis of the respective bolt 50 when the nut 52 is tightened. This foot 55 bears against the blade portion 26 closely adjacent the end of the screw 41 so that heat conduction to the fins 42 along the metal screws is immediate. Each block has a rebate 58 to provide a shoulder cooperative with a fuse link for controlling the positioning of this fuse link and assuring that adequate contact surface areas 40 are engaged for safe transmission of the rated amperage and to assure heat conduction from the fuse link into the clamping parts. Each block 51 has its central part, adjacent the bolt 50, spaced from the blade portion 26 to afford ventilation and to assure that the clamping effort 45 is exerted upon the fuse end and the foot 55.

The fuse link in Figs. 1, 2 and 5 has the heat-absorption portions 60, 61 which are separated by a fusible portion 62 of narrower and thinner cross-section. End contact portions 63, 64 are separated from the portions 60, 61 by 50 fusible portions 65, 66 of narrower and thinner cross-section than the portion 62. Such links may be formed intergrally, by a die-casting operation, from zinc.

The fuse link of Fig. 6 has the general body 70 with lateral notches 71 dividing it into a succession of portions 55 of greater and lesser cross-section. The ends have the notches 72, 73 which are received around the bolts 50. Since such links are of differing thickness according to the amperage to be tolerated, the clamp blocks 51 are 60 reversed in position, Fig. 4, in such cases, to give a firm and solid seating for safe conduction of the current and heat.

In operation with Figs. 1 and 2, if the current gradually increases, the heating effects likewise increase; but the heat is conducted away from the smaller sections which 65 exhibit the highest resistance and heating effects, with the portions 60, 61, 63, 64, and thence are dissipated by direct radiation or by conduction to the blade portions 26 and thence to the fins 41 or the outer blade portions 20, 25, for radiant dissipation. Ultimately with 70 such slowly increasing current values, or after an essentially definite time interval at a current intensity above that continuously tolerated (i. e. the rated capacity), the

radiation losses are insufficient to dissipate the heat, and the fuse link melts or "blows" at a smaller section, thereby interrupting the current flow. Such delayed fuse action is known in the art, but the present employment of clamping elements which effect withdrawal of heat from an end block 63, 64, closely adjacent a portion of small section permits a control upon the condition at which such small section will melt. In the event of a sudden high current flow, as with a short circuit, the link melts at once, as there is insufficient time for significant heat conduction.

The operation with Fig. 4 is the normal one for such fuse links.

It is obvious that the illustrative form is not restrictive, and that the invention may be employed in many ways within the scope of the appended claims.

What is claimed is:

1. In a fuse assembly having terminal conductor members and a fuse link connecting said terminal members, said fuse link having a contact portion at its end, the combination of a clamp block of electrically and thermally conductive material, said block having a surface which at one end of the block has an area in electrically and thermally conductive bearing relation with the fuse link, said block having a rebate on said surface for providing the area of said bearing relation, said rebate providing a shoulder for abutting a surface of the fuse link and locating the same upon the said terminal member, said block having at its other end a foot engaged with said terminal member, said surface being spaced from said terminal member for the portion between the fuse link and the foot, said terminal member being apertured, a clamp bolt engaged in a said aperture and passing through said clamp block and through the said spaced part of the surface thereof, and a locating part on said foot engaged in another said aperture for preventing rotation of the block about the bolt axis, said clamp bolt being effective to hold said fuse link in electrically and thermally conductive relation with both the terminal member and the block.

2. In a fuse assembly having a casing sleeve and end-closing means therefor, terminal conductor members and parts within the sleeve and parts projecting through the end-closing means at the ends of the sleeve and supported thereby, a fuse link within the sleeve and extending between the terminal conductor members and electrically connected thereto, a plurality of heat-conductive and heat-dissipating fins located within the sleeve and positioned longitudinal of the sleeve and parallel to the fuse link, spacing means between the fins, and a metal fin-clamping means engaged in a said terminal member and engaging and holding said fins in heat-conductive relation to said terminal member.

3. In a fuse assembly having a casing sleeve and end-closing means therefor, terminal conductor members and parts within the sleeve and parts projecting through the end-closing means at the ends of the sleeve and supported thereby, a fuse link within the sleeve and extending between the terminal conductor members and electrically connected thereto, a plurality of heat-conductive and heat-dissipating fins located within the sleeve and positioned longitudinal of the sleeve and parallel to the fuse

link, spacing means between the fins, an insulating bridge intervening between said terminal members and spaced therefrom, and a metal clamping means engaged with the said bridge and in a said terminal member and effective to clamp the fins between the said bridge and said terminal member and in heat-conductive relation with the said terminal member.

4. In a fuse assembly having a casing sleeve and end-closing means therefor, apertural terminal conductor members and parts within the sleeve and parts projecting through the end-closing means at the ends of the sleeve and supported thereby, a fuse link within the sleeve and extending between the terminal conductor members and electrically connected thereto, clamping blocks each comprising a metal body having at one end a foot for engaging each of the terminal members, said foot having a projecting part for entering a first aperture of the terminal member, said body having at the other end a rebate for receiving the fuse link with a rebate wall bearing upon the fuse link, the rebate providing a shoulder for engaging and locating the adjacent end of the fuse link, said block having between the said foot and the said shoulder a bolt-receiving aperture for alignment with a second aperture of the terminal member when the projecting part is in the first aperture.
